HYDRAULIC DISRUPTION OF SOLIDS

William Frederick Court, Webster Groves, Mo., as-
signor to Shell Development Company, San
Francisco, Calif., a corporation of Delaware

Application June 14, 1938, Serial No. 213,607

5 Claims. (Cl. 15—104.12)

This invention relates to the hydraulic disruption of solid masses by means of water jets which are directed substantially radially outwardly from a well in the mass, and is particularly concerned with an improved nozzle head which is suitable for that purpose. Such a nozzle head is useful in the removal of solids, like coke, from vessels, but may be employed for other purposes.

10 In my copending application, Serial No. 191,685, filed February 21, 1938, of which this is a continuation-in-part, I have described particularly a process for cleaning vessels which contain solids, like carbonaceous material, particularly deposits of coke produced by the carbonization of hydrocarbon oils, such as reaction and coking chambers employed in petroleum cracking plants and the like, and asphaltic material, especially the solid, brittle kind, by means of water jets. According to one embodiment of the process the body of material to be removed, such as coke in a vertical cylindrical coking chamber, is acted upon in three operations:

In the first step, after opening the top and bottom manholes and cooling the coke by means of steam followed by water, the body of coke is canulated vertically, either by drilling or by means of a vertically, preferably downwardly, directed jet of water, such as, for example, a jet discharged from a spear nozzle with a $\frac{1}{8}$ or one inch diameter orifice, supported by and supplied through a vertical water feed pipe, and discharging water at between 400 and 750 gallons per minute. When water is used, the fine particles of coke displaced are diffused into the body of the coke bed, and the water drains through the coke, discharging through the lower manhole. In this step a vertical hole from one to several inches in diameter is formed through the coke bed at the axis of the chamber. The purpose of this step is to provide a tubular opening or well to permit a water feed pipe, which is suspended and supplied with water at its upper end, and supports the nozzle head employed in the subsequent steps, to be lowered through the body of the coke.

In the second step the opening is reamed to increase the size of the initial opening to about 18 to 24 inches in diameter so that the nozzle head employed in the last step may be used without fouling the coke bed. For this purpose the water feed pipe, which after the jetting in the first step is suspended within the coke bed, is lowered to extend through the lower manhole, and a reaming nozzle head is attached to the lower end in place of the spear nozzle. The assembly is then raised

gradually or step-wise with the water pressure turned on. The reaming nozzle head comprises a rotor, rotatable about the axis of the water feed pipe and is a relatively small radial dimension, having about twice to three times the diameter of the initial hole. It is provided with a plurality of reaction nozzles, which impart a relatively high rotary speed, such as about 1000 revolutions per minute to the head, and with a scraper on top. The nozzles discharge jets of water tending upwardly which cut an enlarged well into the solid material. The second step is completed when the nozzle head has reached the top of the coke bed. Coke which is cut away or loosened by the nozzle head drops down through the opening into dump cars located beneath the coke chamber, and water is collected by means of a pair of inclined aprons, which direct it into a trough, from which it flows into a settling basin, for recirculation through the water feed pipe.

In the third step (which may be begun before the completion of the second step), the main body of the coke is disrupted and completely removed from the chamber. The water feed pipe is again lowered to extend beneath the coking chamber, the reaming nozzle head is disconnected, and the main nozzle head is attached in its stead. Alternatively, the main nozzle head may be coupled beneath the reaming nozzle head. The main nozzle head is nonrotatably connected to the water feed pipe, and is provided with a plurality of upwardly and with a plurality of downwardly directed nozzles which direct jets of water radially outwardly to disrupt and completely remove the coke from the chamber when the water supply is turned on and the nozzle head is raised into the enlarged well. Some of the nozzles on the main nozzle head are arranged to impart a rotary motion to the nozzle head, whereby the nozzles assume a plurality of successive orientations, the rate of rotation being usually regulated by means of a brake operating on the water feed pipe so as not to exceed 2 to 4 revolutions per minute. If desired, the rotation may be effected by applying an external rotating force on the feed pipe, it being in this case unnecessary to arrange the cutting nozzles to impart a turning moment to the nozzle head.

An object of the present invention is to provide a nozzle head which may be employed to effect simultaneously the first and second steps of the process as outlined above. While the nozzle head described in the present application is particularly adapted for the removal of carbonaceous material by the process of the said parent appli-

cation, it may be employed for any operation in which it is desired to form an opening through a mass of solid material, either continuous or packed, and irrespective of whether the operation 5 results in the complete removal of solid material from the container. Thus, in the case of containers of relatively small diameters, a single passage of the nozzle head according to the present invention may completely remove the solids; 10 when containers of greater diameters are encountered, a tubular opening is cut therethrough. A further object of the invention is to provide a nozzle head which will cut a hole of a relatively small diameter through a body of solid material, 15 by the action of a mechanical cutting tool, either alone, or aided by an axial jet, and which will enlarge the hole by the cutting action of water jets.

While it is preferred, for purposes of convenience in connection particularly with the cleaning of coke chambers, and to simplify the mechanical arrangement for guiding and supporting the water feed pipe, to move the nozzle head downwardly in the position shown in the drawings, it 20 should be noted that it is possible to invert it and move it upwardly, or in any other desired direction, depending upon the material being worked upon or the shape of the container. For convenience, the notations "above" and "below," 25 etc., have been used consistently in this specification and claims to describe the device positioned as shown in the drawings, it being understood that these terms are relative, and impose no 30 restriction upon the use of the nozzle head.

With the above and other objects in view, which will become apparent from the following detailed description, the invention resides in the construction and combination of parts described and claimed herein, considered together with the 40 accompanying drawings, in which:

Figure 1 is a vertical sectional view, partly in elevation, of the nozzle head;

Figure 2 is a bottom plan view of the device shown in Figure 1;

Figure 3 is a schematic vertical sectional view, partly in elevation, illustrating one method of using the nozzle head;

Figure 4 is an elevation view, partly in section, of the lower rotating portion of a modified form 50 of the nozzle head;

Figure 5 is a bottom plan view of the device shown in Figure 4;

Figure 6 is an enlarged detail view of the edge of the cutting plate taken on line 6-6 of Figure 1; and

Figure 7 is a longitudinal sectional view of a nozzle suitable for the devices shown in Figures 1 to 4.

Referring to Figures 1, 2, and 3, a supporting pipe 1 is provided with external drill pipe threads at its upper end, adapted for connection with a vertical water feed pipe 2 (see Figure 3) and with an out-turned flange 3 at its lower end. A pair of ball bearing nests, 4, 5, are mounted on 60 the pipe 1 with their inner races in engagement with the exterior of the pipe 1, the inner race of the lower nest 4 resting on the flange 3, and the inner race of the upper nest 5 being spaced therefrom by an inner spacing sleeve 6. 65 A threaded retaining ring 7, secured against rotation by a set screw 8, retains the upper inner race in position. An annular bead is provided on the upper face of the retaining ring.

The rotor comprises a housing 9 which may be 70 slid downwardly over the bearing nests and over

an outer spacing sleeve 10, which separated the outer races of the bearing nests. The housing 9 is provided with a hole 11 for the introduction of a lubricant, which reaches the bearing nests by way of an annular groove 12 on the outer face 5 of the spacing sleeve 10 and one or more holes 13 passing through the sleeve. A rotating ring 14, which may be mounted on the pipe 1 prior to the bearing nests, supports the outer race of the lower bearing nest 4, being itself supported by 10 the flange plate 15, which is secured to the out-turned flange 16 of the housing 9 by means of studs 17. The inner face of the top of the housing 9 is chamfered at 18 to receive the annular bead on the retaining ring to prevent the escape 15 of bearing grease. A gasket 19 may be interposed between the bottom of the housing 9 and the flange plate 15, sealing the rotating ring 14 against the flange plate 15.

The flange plate 15 has a central hole, in which 20 a cup 20, (which may be constructed of a short piece of seamless pipe closed by a welding head) forming a conduit means in communication with the pipe 1 is secured, as by welding. The upper edge of the cup 20 is provided with an annular 25 bead, fitting into a groove 21 in the lower face of the flange 3. The ring 14 is also chamfered as shown. The construction of the ring 14 and the bead on the cup 20 prevent the flow of water into the bearing nests, and the escape of bearing grease therefrom. The outer edges of the flange 16 and the flange plate 15 are similarly chamfered, as shown at 15a.

Four cutting plates or blades 22 are welded to the lower face of the flange plate 15 and to the cup 20. These plates are approximately in the shape of sectors of a circle, as shown, extending radially beyond the flange plate 15. The outer edges 23 are shaped as cutting edges, bevelled to approximately 15° (see Figures 2 and 6) and are 40 hardened. They may, for example, be made of stellite alloy and ground.

A spear nozzle 24 with a smooth, gradually tapering bore 25 is threadedly mounted at the bottom of the cup 20, and is shaped to direct a 45 substantially confined jet of water downwardly. It is preferably, but not necessarily, located coaxially with the axes of the pipe 1, and preferably located entirely above the lower edge of the cutting blades, so as to be protected thereby.

Four curved conduits 26 are mounted in communication with the interior of cup 20, as shown in Figure 2, shaped to supply water to stub nozzles 27, mounted in the blades 22, disposed to discharge substantially confined jets of water 55 horizontally, in a direction perpendicular to the face of the blades. These nozzles 27 may be constructed as shown in Figure 7, with a smooth, gradually tapering bore 28. While the nozzles 27 have been shown to be mounted to discharge horizontal streams, tangential with respect to the axis of the nozzle head, so as to impart the maximum turning force to the rotor, some or all of them may be inclined downwardly, as shown in Figures 4 and 5, or even upwardly. It is desirable to locate the nozzles 27 and conduits 26 wholly within and above the cup-shaped surface of revolution described by the cutting edges upon the rotation of the rotor, whereby the nozzles and conduits are protected against impact with coke.

A plurality of conical tips 29, constructed of heat treated tool steel, and provided with threaded shanks 30, are mounted on the flange 16, to prevent coke which may become loosened and

bridge the opening from stopping the rotation of the rotor.

A plurality of semi-circular indentations 31 are cut into the outer edge of the flange plate 15 and the flange 16. These indentations are bevelled at the trailing edges 31a so as to permit water to rise through the indentation when the rotor is in operation.

10 Operation (Figure 3)

Although the nozzle head may be used for other purposes, its use will be described in connection with the cleaning of a coke or reaction chamber. Referring to Figure 3, 32 represents a vertical cylindrical coke chamber of the usual cracking installation which may, for example, be 40 feet in height and 10 feet in diameter. 33 represents a body of coke which has been deposited therein. To cannulate the coke bed and ream the opening (these operations corresponding to the first two steps of the process described above), after the removal of the top and bottom manhole covers and at least partially cooling the coke, the nozzle head is attached to the water feed pipe 2, 20 suitably supported from the top, and lowered into the chamber from a point above the coke chamber, full water pressure being turned on when the nozzles 27 have entered the chamber.

The water discharging from the spear nozzle 24 30 pierces a hole 34 several feet ahead of the cutter blades. The reaction of the water discharging through the nozzles 27 causes the rotor to revolve at a high speed, such as, 1000 revolutions per minute. The nozzle head is gradually lowered 35 bringing the cutting edges 23 of the cutting plates 22 into engagement with the coke, whereby they will cut a tubular opening through the coke. At the level of the nozzles 27 this opening will be enlarged as shown at 35 by the cutting 40 action of the tangential water jets.

The diameter of the opening formed by the action of the tangential water jets will usually be from 1½ to 2½ times the diametric distance between the upper portions of the cutting edges 45 23. The assembly is gradually lowered until the nozzle head extends through the bottom manhole 36. During the downward passage of the nozzle head the fine particles of coke and the water are diffused through the coke bed, the water discharging through the lower manhole 36. The action of the jet from the nozzle 24 provides a substantial area for the seepage of water into the coke bed in view of the fact that the bottom of the hole 34 will be several feet below the cutters 22. If the rate of water flow into the coke bed below the nozzle head is insufficient, the excess water and, at times, coke will flow upwards around the flange plate 15 and through the indentation 31 entering the body of the coke at 50 points above the nozzle head. At times small quantities of the disintegrated coke will build up above the nozzle head but these quantities were found to be insufficient to retard the speed of rotation appreciably and to interfere with the 55 cutting operation.

In the modifications illustrated in Figures 4 and 5, the pipe 4, housing 9, and the bearing and lubrication arrangements are the same as illustrated in Figure 1. The lower portion of the rotor 0 comprises the flange plate 15' with indentations 31', 31a', supporting a cup 20', cutting plates 22', with cutting edges 23', all as in Figure 1. Instead of a spear nozzle, the modified assembly comprises a star shaped drill 31, provided with a plurality, 5 such as 5, cutting edges. The shank 38 of the

drill is welded to a square plate 39 having a central hole housing the shank 38. The plate 39 is secured to the cutting plates 22' by welding as shown in Figure 5.

The curved conduits 28' are in communication 5 with the cup 20' and with the nozzles 27', mounted in the cutting plates 22', the only difference between this construction and that previously described being that the axes of the nozzles 27' are inclined downwardly at an angle of about 10 30° below the horizontal. This arrangement causes the water jets from the tangential nozzle 27' to cut the hole in advance of the upper portions of the cutting plates 22', thereby reducing the load placed upon the latter.

15 The nozzle head of Figures 4 and 5 may be employed in the manner described above.

The sizes of the nozzles and rates of discharge may be varied with the size of the installation and the particular purpose to be effected. By 20 way of example, it may be stated that for cutting a tubular opening through a coke chamber of the type and size described above, the diametric distance between the upper outer portions of the cutting plates 22 or 22' may be 12½ inches; 25 the diameter of the orifice of the spear nozzle 24 may be $\frac{1}{8}$ inch; and that of the tangential nozzles 27 and 27' may be $\frac{1}{16}$ inch, although, for the installation described, spear nozzle orifices of from about $\frac{3}{16}$ to $\frac{1}{4}$ inch diameters, and tangential nozzles of from $\frac{1}{16}$ to $\frac{1}{8}$ inch diameter may usually be employed. Sufficient water pressure is applied to the water feed pipe 2 to cause 30 the total rate of discharge to be between about 400 and 900 gallons per minute.

35 Such rates of discharge will cause the water jets to have velocities of between about 100 and 500 feet per second, preferably above 250 feet per second. It is desirable to employ orifices having smooth bores so that the jets will not substantially break up or spread prior to impact, whereby erosion is minimized and cutting of the jet is materially increased.

40 While I have given particular dimensions suitable for a particular installation, it is understood that this invention is not limited thereto, but may be employed in connection with other rates of water flow and sizes of orifices without departing from the spirit and scope of the invention.

I claim as my invention:

1. In a nozzle head for cutting into a body of solid material, the combination of a vertical conduit adapted for connection with a source of liquid under pressure, a rotor rotatably mounted on said conduit, one or more cutters having 55 cutting edges extending beneath the conduit and radially outwards from the axis thereof, reaction nozzle means on said rotor in flow communication with said conduit arranged to impart a turning motion to said rotor, and a substantially 60 downwardly directed spear nozzle located entirely above the lower edge of the cutter, disposed to cut a well into said solid material beneath said cutting edge, whereby the downwardly directed nozzle is protected by said cutter.

65 2. In a nozzle head for cutting into a body of solid material, the combination of a vertical conduit adapted for connection with a source of liquid under pressure, a rotor rotatably mounted on said conduit, a conduit means on said rotor 70 in flow communication with said conduit, a plurality of cutting blades on said rotor extending substantially radially outwardly and beneath said conduit member having cutting edges facing outwardly and downwardly, a plurality of reaction 75

nozzles supported by said cutting blades, arranged to impart a turning motion to said rotor, means for supplying liquid from said conduit means to said reaction nozzles, the reaction nozzles and 5 the means for supplying liquid thereto lying within and above the surface of revolution described by the cutting edges upon the rotation of the rotor, and means for cutting a well into said solid material beneath said cutting edges.

10 3. In a nozzle head for cutting into a body of solid material, the combination of a vertical conduit adapted for connection with a source of liquid under pressure, a rotor rotatably mounted on said conduit, a conduit means on said rotor in 15 flow communication with said conduit, a plurality of cutting blades on said rotor extending substantially radially outwardly and beneath said conduit member having cutting edges facing outwardly and downwardly, a plurality of reaction 20 nozzles supported by said cutting blades, arranged to impart a turning motion to said rotor, means for supplying liquid from said conduit means to said reaction nozzles, and a substantially downwardly directed spear nozzle in communication with said conduit means arranged to 25 cut a well into said solid material beneath said cutting edge, said reaction nozzles, said means for supplying liquid thereto, and said spear nozzle all lying within and above the surface of revolution.

tion described by the cutting edges upon the rotation of the rotor.

4. In a nozzle head for cutting into a body of solid material, the combination of a vertical conduit means adapted for connection with a source 5 of liquid under pressure, a rotor rotatably mounted on said conduit, a plurality of cutting blades on said rotor extending beneath the conduit and substantially radially outwards from the axis thereof, a plurality of reaction nozzles 10 supported by said cutting blades and means for supplying liquid from said conduit means to said reaction nozzles.

5. In a nozzle head for cutting into a body of solid material, the combination of a vertical conduit 15 adapted for connection with a source of liquid under pressure, a rotor rotatably mounted on said conduit, a plurality of cutting blades on said rotor extending beneath the conduit and substantially radially outwards from the axis 20 thereof, a plurality of reaction nozzles supported by said cutting blades and arranged and disposed to discharge liquid jets substantially outwardly and downwardly, means for supplying liquid from said conduit means to said reaction nozzles 25 and means for cutting a well into said solid material beneath said cutting blades.

WILLIAM FREDERICK COURT.
